UNITED STATES PATENT OFFICE

112,512

DESIGN FOR A DISPLAY PLATFORM FOR RUGS OR THE LIKE

Leon H. Best, Galva, Ill., assignor to John H.
Best & Sons, Inc., Galva, Ill., a corporation of Illinois

Application November 24, 1937, Serial No. 73,173

Term of patent 7 years

To all whom it may concern:

Be it known that I, Leon H. Best, a citizen of the United States, residing at Galva, in the county of Henry and State of Illinois, have invented a new, original, and ornamental Design for a Display Platform for Rugs or the like, of which the following is a specification, reference being made to the accompanying drawing, forming a part thereof in which Fig. 1 is a side elevational view; Fig. 2 is a perspective view; and Fig. 3 is a bottom plan view of the article showing my new design.

The characteristic features of my design reside in a platform of the specific configurations and proportions shown having a cross member adjacent one end thereof and being inclinedly supported lengthwise on end supporting members of the specific configurations and in the manner shown.

I claim:

The ornamental design for a display platform for rugs or the like, as shown and described.

LEON H. BEST.
